(57) **CLAIM**

The ornamental design for the earphones, as shown and described.

DESCRIPTION

FIG. 1 is a rear view of a first embodiment of an earphone embodying our design;

FIG. 2 is a top view thereof;

FIG. 3 is a left side elevational view thereof;

FIG. 4 is a front view thereof;

FIG. 5 is a right side elevational view thereof;

FIG. 6 is a bottom view thereof;

FIG. 7 is a perspective view thereof;

FIG. 8 is a rear view of a second embodiment of an earphone embodying our design;

FIG. 9 is a top view thereof;

FIG. 10 is a left side elevational view thereof;

FIG. 11 is a front view thereof;

FIG. 12 is a right side elevational view thereof;

FIG. 13 is a bottom view thereof; and,

FIG. 14 is a perspective view thereof.
